PLAY TABLE WITH CHILD-RETAINING TETHER

**Joe Spaulding, 365 West End Ave.,
New York, N.Y. 10024**

Filed Sept. 25, 1967, Ser. No. 8,729

Term of patent 3½ years

(Cl. D34—15)

FIG. I

FIG. 2

FIG. 3

FIG. 1 is a top perspective view of the play table, with the child-retaining tether, showing my new design.

FIG. 2 is a top plan view.

FIG. 3 is a fragmentary transverse view upon the line 3—3 of FIG. 2.

I claim:

The ornamental design for play table with child-retaining tether, as shown and described.
